UNITED STATES PATENT OFFICE.

LYMAN C. HUFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA.

PROCESS FOR TREATING RESIDUAL OILS.

Application filed May 26, 1924. Serial No. 715,827.

My invention relates to process and apparatus for treating residual oils, and refers more particularly to the idea of utilizing the residue obtained from the distillation of hydrocarbon oils, with particular reference to destructive distillation under conditions of cracking temperatures and pressure.

In the particular embodiment of this invention, the residue is withdrawn from the reaction chamber of a cracking plant and passed to an enlarged chamber, the pressure maintained during the cracking operation being materially reduced. Due to the reduction of pressure and the latent heat retained in the residue, the light constituents of said residue will vaporize, said vapors being withdrawn and condensed. The unvaporized residue may be withdrawn and forced to the fuel oil circulating system hereinafter described, the excess being returned to the bulk supply maintained in said enlarged chamber.

Many advantages of my invention will occur to those skilled in this art. Among some of these advantages are the production of a maximum yield of light hydrocarbons and the utilization of the entire residue as fuel oil in the plant, any excess being returned to the supply maintained in the enlarged chamber. The unvaporized residue is continually caused to circulate through a fuel system about the refinery supplying the burners for stills, boilers, etc., and any excess being returned as heretofore described.

In this manner the lighter ends of the residuum will be removed, leaving a heavy liquid residue which, instead of being reduced to coke as is the present practice in a coking still, is disposed of by utilizing same in a fuel burning system. It will be seen that the enlarged chamber containing the bulk supply acts as a combined flash still and equalizing fuel oil storage or supply.

In drawings, Fig. 1 is a side elevational view partly in vertical section, showing in detail the combined flash still and bulk supply storage tank. Fig. 2 is a diagrammatic showing of the fuel oil re-circulating system.

Referring in detail to the drawings, 1 designates an enlarged chamber which, in the present instance, takes the form of a vertical tower provided with a liquid gauge glass 2, vapor outlet pipe 3, safety valve 4, residue inlet pipe 5, controlled by valve 6. The vapor line 3 may be connected with any suitable form

of condenser such as shown at 7, which latter is connected by pipe 8 to the rundown tank or receiver 9; the chamber 1 is preferably insulated as shown at 10.

The residue preferably from a concurrently operated cracking operation, which may be at a temperature of from 400 to 700° F., may be introduced adjacent the top of the chamber 1 through the inlet pipe 5, the valve 6 regulating the reduction in pressure which may be down to, say, atmospheric. The inclined baffles 11 may be provided adjacent the residue inlet for the purpose of providing releasing surface for the lighter ends which vaporize due to the latent heat retained in the residue and the reduction in pressure, these lighter ends passing off through the vapor outlet pipe 3 to the condenser coil 7 and discharged to the receiver 9 as explained.

The unvaporized portion of the residuum falls to the lower portion of the enlarged chamber 1 and may be withdrawn through the suction line 12. The suction line 12 may be connected to the pump 14, which may discharge residue through the strainer or filtering member 15, the valves 16 and by-pass valve 17 being provided. The residue is then forced into the circulating fuel oil header 18 which encircles the refinery supplying fuel oil to furnaces of the various stills, boilers, cracking plants, etc. In the header 18 the oil is preferably maintained under the pump pressure and may be fed to the stills 19 connected to the header by the connecting lines 20, the latter having interposed therein valves 21. The oil may be fed to the boilers 22, the latter being connected to the header 18 by the pipe connections 23, in which are interposed the valves 24. The excess oil which is being re-circulated by pump 14 may be returned through a continuation of the header 18 and 95 may discharge into the lower portion of the enlarged chamber 1 through the inlet pipe 25, in which is interposed the valve 26. As shown clearly in Fig. 2, the extremity of this pipe 25 is preferably curved, as shown as 27, to conform with the curvature of the chamber 1 and assist in maintaining the oil in the bottom of said chamber in a constant state of swirling motion or agitation, and preventing settling of any carbon or other foreign matter suspended therein. The pump 14 may be equipped with the usual pressure governor to maintain a constant pressure on the header

18, and by the manipulation of the valve 26 a definite quantity of oil can be caused to circulate through the system.

It may be desirable to assist the vaporization within the chamber 1 to obtain a higher yield of the lighter ends. For this reason a pipe 28 connected to any source of steam supply may discharge into the interior of the chamber 1 where it mixes with the oil therein, this steam is preferably superheated to a temperature higher than the incoming oil. Steam may also be mixed with the hot residuum at a point adjacent the reaction chamber where said residue is released from the cracking operation; the steam thus acting to convey the heavy residuum into the enlarged separating chamber 1. When there is an excess of residue in the chamber 1 other than what is being consumed by the furnaces of the stills 19 and boilers 22, this excess may be diverted from the continuation of the header 18 into storage tank 29 through the pipe connection 30 in which is interposed valve 31, the valve 26 being then closed, if desired. On the other hand, when the demand for fuel oil in the system is in excess of the amount of oil maintained in the bulk supply in the chamber 1 the deficiency can be remedied by withdrawing oil from the storage tank 29 through the pipe connection 32, in which latter is interposed the valve 33. The oil withdrawn from the storage tank 29 may have a suction imposed on it by the pump 14, and this oil diverted into the fuel-burning system, the valve 34 in the line 35 connected to the pipe 32 being preferably closed. A drain 36 provided with valve 37 may be provided adjacent the bottom of the chamber 1.

It is to be noted that in the preferred method of operation the upper portion only of the chamber 1 may be insulated as shown at 10, in order to reduce the temperature of the liquid oil in the lower portion, if same is desirable, before it is sent to the fuel-burning system. It must be understood, of course, that the chamber may be entirely insulated. Also the chamber 1 instead of being vertical may lie in a horizontal plane. In the preferred form of operation it is to be noted that the chamber 1 is unheated either internally or externally. A steam spray 38 may be positioned below the liquid level of the oil to further assist in the distillation of the lighter ends. I do not wish to limit myself to effecting a distillation within the chamber 1 at atmospheric pressure, as in place of the rundown tank 9 a receiver may be provided, and a vacuum created therein by means of a vacuum pump which would maintain a vacuum in the condensing coil 7 and enlarged chamber 1 to promote further distillation.

The oil level is preferably maintained at the level shown at 39 although this is, of course, within the option of the operator.

From the foregoing it will be seen that I have provided an economic process and apparatus for commercially utilizing the residue obtained from the cracking or distillation of hydrocarbon oils, at the same time producing a maximum yield of light hydrocarbons. By returning the excess residue from the stills and boilers to the combination flash still and bulk supply storage, it is possible to utilize 100% of the residue as fuel oil. The economic value of this will be appreciated without any further enumeration of its many advantages. The residue in the header 18 being in a heated liquid condition will not clog the circulating system, therefore allowing the use of residues which are more or less naturally viscous.

I claim as my invention:

1. An improved method for utilizing the liquid residue from a hydrocarbon oil cracking process, which comprises withdrawing the residual oil from a pressure cracking still, while at a temperature in excess of 400° F., lowering the pressure on the liquid residue, introducing the same to an enlarged zone, taking off vapors from said enlarged zone which have been evolved from the residual oil therein, in maintaining a body of the heated residual oil in said enlarged zone, continuously circulating the hot residual oil through a closed ring, including said enlarged zone, and supplying regulated quantities of the hot residual oil from said closed ring to selected furnaces positioned adjacent the ring, to constitute the fuel consumed therein.

2. An improved method for utilizing the heavy residual oil from a hydrocarbon oil cracking process as a fuel, which comprises forcing the hot residual oil produced in a concurrently operated cracking still from said still into an enlarged zone, wherein a substantial body of the hot residual oil collects, continuously circulating the hot residual oil in a closed ring, including said enlarged zone, in removing regulated quantities of the hot residual oil from said closed ring, and introducing the same in a heated condition to selected furnaces positioned adjacent the ring, to supply the fuel consumed in such furnaces.

3. An improved method for utilizing the liquid residue from a hydrocarbon oil cracking process, which comprises withdrawing the hot residue from a cracking still, at a temperature in excess of 400° F., introducing such hot residues to an enlarged zone, maintained under a lower pressure than that employed in the cracking process, taking off vapors evolved from the oil as a result of the reduction in pressure from said enlarged zone for condensation, in maintaining a substantially constant volume of the heated residual oil in said enlarged zone, in continuously circulating hot residual oil through a closed ring, including said enlarged zone, and sup-

- plying regulated quantities of the hot residual oil from said closed ring to selected furnaces positioned adjacent said ring, to constitute the fuel consumed in such furnaces, and applying additional heat to the body of oil maintained in said enlarged zone. 5
4. An improved method for utilizing the heavy residual oil from a hydrocarbon oil cracking process as a fuel, which consists in forcing the hot residual oil produced in a concurrently operated cracking still from said still into an enlarged zone, wherein a substantial body of the hot residual oil collects, in continuously circulating the hot residual oil 10 in a closed ring, including said enlarged zone, in removing regulated quantities of the hot residual oil from said closed ring and in introducing the same in a heated condition to selected furnaces positioned adjacent the ring, to supply the fuel consumed in such furnaces, and in introducing steam into said enlarged zone, at a temperature above the temperature of the oil in said enlarged zone, to elevate the temperature of the oil in said 15 enlarged zone. 20
5. An improved method for utilizing the heavy residual oil resulting from the cracking of hydrocarbon oil in a concurrently operated cracking still which consists in forcing the hot residual oil, under the pressure employed in the cracking process from said cracking still, into an enlarged zone, maintained under a lower pressure than the pressure employed in the cracking process, in collecting a substantial body of hot residual oil in said enlarged zone, in maintaining a forced cyclic circulation of the hot residual oil through a closed ring, including said enlarged zone, in removing regulated quantities 25 of the hot residual oil at spaced points in the ring, in supplying such regulated quantities of the residual oil removed from the ring to furnaces positioned adjacent the ring, to constitute the fuel consumed in such 30 furnaces. 40
6. An improved method for utilizing the liquid residual oil resulting from the cracking of hydrocarbon oil in a concurrently operated cracking process, which comprises introducing the residual oil directly from a 45 cracking still, without substantial decrease in temperature, into an enlarged zone, maintaining a lower pressure in said enlarged zone than that maintained on the residual oil in the cracking still, in taking off vapors evolved 55 from the residual oil as a result of the decrease in pressure from said enlarged zone for condensation, in collecting a substantial body of the hot residual oil in said enlarged zone, in continuously circulating the hot residual oil, under a mechanically applied pressure, through a closed ring, including said enlarged zone, in removing regulated quantities of the hot residual oil from said closed ring and in supplying such regulated quantities, 60 while in a heated condition, to selected furnaces positioned adjacent said closed ring, to constitute the fuel consumed therein, in removing an additional quantity of oil from said closed ring, when the volume of oil in 65 the ring becomes excessive, and in admitting additional oil to the ring from a source other than said enlarged zone, when the quantity of oil in the ring decreases below the amount desired to be maintained in said ring. 70
7. An improved method for utilizing the heavy residual oil from a hydrocarbon oil cracking process, which consists in removing the hot residual oil from a cracking process, in introducing the removed residual oil, without substantial drop in temperature, into an enlarged zone, wherein a substantial volume of the hot residual oil is maintained, in continuously withdrawing hot residual oil from said enlarged zone, in placing the same under 75 a mechanically applied pressure, in passing the same, while moving under a mechanically applied pressure, through a filter, in delivering regulated quantities of the oil, while moving under a mechanically applied pressure, to selected furnaces, to supply the fuel consumed therein and in returning the remaining oil which has been placed under a mechanically applied pressure to the body of oil in said 80 enlarged zone, and in so controlling the introduction of such oil to the enlarged zone that the body of oil therein is maintained in a turbulent condition. 85
